(57) **CLAIM**

The ornamental design for a supporting leg for vacuum cleaner as shown and described.

DESCRIPTION

1. Supporting leg for vacuum cleaner
1.1 : Front perspective view of a supporting leg for vacuum cleaner showing our new design;
1.2 : Back perspective view thereof;
1.3 : Front view thereof;
1.4 : Back view thereof;
1.5 : Left view thereof, right view is omitted because it is a mirror image of the left view;
1.6 : Top view thereof;
1.7 : Bottom view thereof;
1.8 : Another perspective view showing a state of use in which the upper part of the claimed design is rotated; and
1.9 : Another perspective view showing another state of use wherein broken lines depict environmental structure and form no part of the claimed design.

1 Claim, 9 Drawing Sheets
